CLAIM

An ornamental design for a case for artificial lash extensions, as shown and described.

DESCRIPTION

FIG. 1 is a front left perspective view of a case for artificial lash extensions in accordance with the present invention.

FIG. 2 is a left side view thereof.

FIG. 3 is a right side view thereof.

FIG. 4 is a front view thereof.

FIG. 5 is a rear view thereof.

FIG. 6 is a top view thereof.

FIG. 7 is a bottom view thereof; and,

FIG. 8 is an exploded front left perspective view of the case for artificial lash extensions shown in FIG. 1.

The broken lines consisting of evenly spaced dashed lines in the drawings illustrate portions of the case for artificial lash extensions which form no part of the claimed design. The shaded areas depict the scope of the claimed design.
